UNITED STATES PATENT OFFICE.

FRED N. ROOT, OF KALAMAZOO, MICHIGAN.

LIFE GUARD FOR STREET CARS OR SIMILAR VEHICLES.

1,414,435.

Specification of Letters Patent. Patented May 2, 1922.

Application filed October 18, 1921. Serial No. 508,421.

To all whom it may concern:

Be it known that I, FRED N. Root, a citizen of the United States, residing at the city and county of Kalamazoo, State of Michigan, have invented certain new and useful Improvements in Life Guards for Street Cars or Similar Vehicles, of which the following is a specification.

This invention relates to improvements in 10 lifeguards for street cars or similar vehicles.

The objects of the invention are:

First, to provide a very simple and effective means for actuation of the cradle and for maintaining it in elevated position 15 until needed.

A further object is to provide a very economical and strong structure which is elastic and consequently especially effective in gathering up obstructions on the track.

Objects relating to details and economies 20 of construction will definitely appear from the description to follow.

I accomplish the objects of my invention by the devices and means described in the 25 following specification. The invention is clearly defined and pointed out in the claims.

A structure which is a preferred embodiment of my invention is fully illustrated in the accompanying drawing, forming a part 30 of this specification, in which:

Fig. I is a perspective view of my improved structure with the cradle in elevated position and the tripping and actuating gate in operative position, any portion of the car to which it is applied being omitted except 35 a fragment of a section of the floor board.

Fig. II is a similar perspective view after the gate has been tripped and the basket has been lowered to receive the obstruction.

Fig. III is an enlarged detail longitudinal 40 sectional view showing the disposition of the parts when the basket is in elevated position and the gate in position to be tripped by an obstruction and actuate the basket.

Fig. IV is a detail view of the lock joint 45 between the gate actuating rocker arm and the connecting link for actuating and holding the cradle.

In the drawing similar numerals of reference refer to similar parts throughout the 50 several views.

Considering the numbered parts of the drawing, 1 is the cradle generally. 2 is the rock shaft carrying the same, and 3 bracket bars for attachment to the under framework 55 of a street car. Transverse slats 4 are car-

ried by the curved spring arms 5 which are conformed into downwardly projecting curved surfaces toward their forward ends at 6, the forward ends being upturned at 7, 8 is an upwardly projecting arm secured to the central part of bars 5 by suitable bolts. 9 is a forwardly extending coiled spring connecting the upper end of the arm 8 to the under side of the platform of the car to insure the very prompt action of the same and also to urge the same downwardly, thereby 65 putting tension upon the lock connection, hereafter to be described.

Attaching brackets 81 are provided at each end of the bars 5. These are short 70 bars turned into eyes 82 at their lower ends and are secured to the end cross bars by bolts 83. The eyes 82 are to embrace the rock shaft 2 and in connection with the said cross bars afford a very effective strong and 75 yet elastic support for the said cradle.

10 is a suspended swinging gate made up of cross bars 11 and transverse slats 12 and suspended on the rock shaft 13 which is supported in suitable brackets 14 adapted to be secured to the under side of the platform or frame of a car. An elbow arm 15 (see Figs. III and IV) having a rearwardly projecting portion 16 is connected by suitable pivots 18 to the link 17, the rear end of which is connected at 17' to the upwardly projecting arm 8 of the cradle. The forward end of the link 17 and the rear portion of the contacting part of the arm 16 are cut with a beveled joint 19; as seen in Fig. IV, so that when the link connection drops below the center a stop 80 limits the downward movement.

An elbow 20 is secured to the slats 12 of the gate at the front and extends rearwardly therefrom and a treadle bar 22 extends through the floor of the car and is provided 85 with a pedal 23.

The action of my improved lifeguard will be readily understood from an examination of the drawing. In the position appearing in Figs. I and III the structure is ready for 100 action. If any considerable obstruction is on the track it will be struck by the swinging gate 10 which will throw the arm 16 upwardly which will carry the forward end of the link 17 upwardly and forwardly with it and break the toggle by which the cradle is held in elevated position and pull the arm 8 forward. Spring 9 at once, by positive action, tends to force the cradle down against 105 the track and the obstruction is received over 110

the front edge thereof. Because the bars 5 are of spring metal and are supported as they are, they yield in the event of any considerable pressure and free themselves from 5 any irregularity on the rail or the track, passing over without injury to the device, but at the same time effectively picking up any obstruction, such as a prostrate human body. The lifeguard is at once again set 10 for action by stepping upon the pedal 23 which swings the gate 10 strongly to the front and, by the toggle, forces the arm 8 secured to the basket, rearwardly against the action of the spring 9, which at once 15 tensions and lowers the whole device as soon as the pivot 18 passes downward past the dead center.

Having thus described my invention, what I claim as new and desire to secure by Letters Patent is:

1. In a lifeguard, the combination of a cradle adapted to be disposed beneath the car, the said cradle comprising angled cross bars of spring metal, a supporting rock shaft therefor secured to the said cradle by suitable cross bars with their lower ends turned into engaging eyes and their upper parts secured to said angled cross bars, an upwardly projecting arm on the said cradle, 25 a suspended pivoted gate with brackets for supporting it under the front portion of the platform of a car, a rearwardly projecting arm on said gate, a pivoted link connecting the rear end of said arm and the upwardly 30 projecting arm on the said cradle with a beveled joint between the said arm and link for limiting its downward movement, and a tension spring adapted to connect the upper end of the arm of the cradle to the under 35 side of the car, and resetting means comprising a rearwardly extending lever arm secured to the said gate with an upwardly 40 disposed treadle piece adapted to extend above the floor of a car, all coacting as specified.

2. In a lifeguard, a cradle adapted to be disposed beneath the car comprising angled cross bars of spring metal with upwardly 45 extending rear portions and forwardly extending lower portions offset downwardly toward their forward ends to form sliding supports and with their ends upturned, transverse slats on said cross bars, a supporting rock shaft disposed within the lower 50 rear part of said cradle, and cross bars with eyes turned therein to embrace the said rock shaft, the upper portions of said eye bars being secured to the angled cross bars, coacting 55 as specified.

3. In a lifeguard, a cradle adapted to be disposed beneath the car comprising angled cross bars of spring metal with upwardly 60 extending rear portions and forwardly ex-

tending lower portions, transverse slats on 65 said cross bars, a supporting rock shaft disposed within the lower rear part of said cradle, and cross bars with eyes turned therein to embrace the said rock shaft, the upper portions of said eye bars being secured to the angled cross bars, coacting as 70 specified.

4. In a lifeguard, the combination of a cradle made up of cross bars of spring metal being upwardly disposed at their rear ends and horizontally disposed towards their forward ends, cross slats therefor, a supporting rock shaft disposed within said cradle and retained thereto by suitable eye bars with upwardly extending part secured to the back 75 part of the cradle, a spring for pulling the same forward, a suspended gate on a suitable rock shaft in front of the said cradle, a rearwardly projecting arm secured to the said gate, a link pivoted to the said arm and pivotally connecting the upwardly projecting 80 arm on the said cradle, the same being provided with a beveled stop joint to limit the movement beyond the dead center, a rearwardly projecting arm on said gate, and a pedal bar connected thereto adapted to extend above the platform of the car, coacting 85 as specified.

5. In a lifeguard, the combination of a cradle made up of cross bars of spring metal being upwardly disposed at their rear ends 90 and horizontally disposed towards their forward ends, cross slats therefor, a supporting rock shaft disposed within the said cradle and retained thereto by suitable eye bars, an upwardly extending arm secured to the back 95 part of the cradle, a spring for pulling the same forward, a suspended gate on a suitable cross bar in front of the said cradle, a rearwardly projecting arm secured to the said gate, a link pivoted to the said arm and pivotally connecting the upwardly projecting 100 arm on the said cradle, the same being provided with a beveled stop joint to limit the movement beyond the dead center, and means to reset said cradle and gate, coacting 105 as specified.

6. In a lifeguard, the combination of a cradle comprising cross bars of spring metal and having an upwardly projecting spring arm secured thereto, a suspended gate, an arm secured to said gate, a pivoted link from the arm on said gate to the arm on said cradle, a beveled stop for limiting the movement past the dead center, and a spring secured to the arm of the said cradle and 115 adapted to connect to the under side of the car, coacting as specified.

In witness whereof, I have hereunto set my hand and seal.

FRED N. ROOT. [L.S.]
